UNITED STATES PATENT OFFICE.

WILLIAM G. STEVENSON, OF CHICAGO, ILLINOIS.

CRUSHING-MACHINE.

1,345,715.

Specification of Letters Patent.

Patented July 6, 1920.

Application filed October 5, 1918. Serial No. 256,945.

To all whom it may concern:

Be it known that I, WILLIAM G. STEVENSON, a citizen of the United States, and a resident of Chicago, in the county of Cook 5 and State of Illinois, have invented certain new and useful Improvements in Crushing-Machines, of which the following is a specification.

My invention relates to improved crushing machines and covers several improved 10 features of construction, arrangement and operation.

Among the important objects of the invention are to produce a simple machine 15 of small size with a large capacity; to produce a machine which is continuous in its operation, that is, into which raw material can be constantly fed and the crushed or ground material continuously delivered 20 therefrom; and to provide a construction involving a plurality of concentric crushing or grinding zones and improved mechanism for transferring the material from one zone to the other.

25 The above and other features of my invention are embodied in a machine shown on the accompanying drawings, in which—

Figure 1 is a side elevational view with parts in section and broken away,

30 Fig. 2 is a plan view with the framework in section on plane 2—2, Fig. 1, and

Fig. 3 is a diametral sectional view of the grinding table.

The foundation 10 preferably of concrete 35 is provided for the machine supporting structure, this foundation forming the pit 11. On the ends of the foundation are secured the metal supporting bases 12 and 12' respectively, from which rise the frames 13

40 and 13' which are secured together near their upper ends by the horizontally extending I beams 14 and 15. The vertical shaft 16 is supported at its lower end in the step bearing 17 mounted on the foundation at 45 the bottom of the pit 11, the shaft being journaled at its upper end in a bearing frame 18 secured to the beam 14. Frame extensions 19 and 19' on the end frames 13 and 13' support bearings for the driving shaft 20 which extends at right angles to 50 the shaft 16 and carries a driving pinion 21 which meshes with the gear 22 secured to the upper end of the shaft 16, the shaft 20 supporting also the belt pulley 23 by 55 means of which it is rotated. Within the pit is the crushing and grinding table 24

secured by its hub 25 to the shaft 16. A cylindrical sheet metal outer wall 26 is supported on the table within the peripheral flange 27 and concentric with this outer 60 wall and with the hub 25 are the annular partition walls 28, 29 and 30. These intermediate walls together with the hub and outer wall form the concentric annular crushing troughs 31, 32, 33 and 34, the 65 grinding plates 35, 36, 37 and 38 presenting a hard grinding surface, being preferably secured to the table to form the bases for the troughs.

Engaging in the trough 31 are the heavy 70 grinding rollers 39 and 40, the rollers being parallel and at opposite sides of the trough, the rollers having the shafts 41 and 42 respectively. Secured to the beams 14 and 15 and extending parallel and downwardly 75 therefrom are the frames 43 and 44 which at their lower ends have the vertically extending rectangular guide ways 45 and 46 respectively for the rectangular bushings 47 and 48 in which the inner ends of the shafts 80 41 and 42 respectively are journaled. Beams 49 and 50 are secured at their outer ends to the end frames 13 and 13' and extend across the pit parallel with and below the beams 14 and 15. Secured to the beams 49 and 50 85 are the frames 51 and 52 which have the rectangular vertically extending guide ways 53 and 54 for the rectangular bushings 55 and 56 in which the outer ends of the shafts 41 and 42 are journaled, the rollers 39 and 40 90 being thus pivoted to revolve and being bodily shiftable vertically as they travel over material to be crushed when the table 24 is rotated.

For the troughs 32, 33 and 34 two sets of 95 rollers 57, 58, 59 and 57', 58', 59' are provided, the sets being diametrically opposite and the rollers being at right angles with the rollers 39 and 40. The rollers of the sets are independently rotatable on 100 shafts 60 and 60', respectively, the axes of these shafts being in the plane of the axis of the shaft 16. On the bases 12 and 12' are supported the bearing frames 61 and 61' which have the vertically extending rectangular bushings 63 and 63' in which the outer ends of the shafts 60 and 60' are journaled. The inner ends of these shafts are journaled in rectangular bushings 64 and 64' slidable vertically in the guide ways 65 110 and 65' of the frames 66 and 66' secured against the sides of the frames 43 and 44.

The rollers in the sets are thus free to rotate independently on their supporting shafts and the sets can shift bodily vertically as the rollers travel over the material during grinding thereof. A spout 67 extends between the beams 14 and 15 and the frames 43 and 44 for discharging into the inner trough 31 the raw material to be treated, and after a preliminary crushing 10 operation in this trough underneath the rollers 39 and 40 the material is conveyed into the next trough 32 and then successively to the troughs 33 and 34 to be discharged from the trough 34. Secured to the beam 49 is the fitting 68 to which is pivoted the forked end of the arm 69, which at its inner end has the lateral extension 70 to which is secured the sheet metal scoop 71. This scoop extends over the partition wall 28 and into the trough 31, its inner edge engaging against the trough base so as to receive material from the trough and convey it over the wall 28 into the next trough 32, the scoop sides 72 being shaped to guide the material and prevent spilling thereof. The arm 69 being hinged at its outer end, the scoop edge will always engage with the floor of the trough 31 to efficiently scoop up the material, any wear on the scoop being thus compensated for.

Secured to the beam 49 is the frame 74 to which are hinged the arms 75, 76 and 77 whose inner ends support the scoops 78, 79 and 80, respectively. The entrance edges 35 of these scoops engage with and extend transversely across the floors of the troughs 32, 33 and 34, respectively, to receive material from these troughs. The outer ends of the scoops 78 and 79 extend over the 40 partition walls 29 and 30 respectively, to deliver material to the troughs 33 and 34 respectively, while the scoop 80 at its outer end extends across the outer wall 26 to deliver the finished product from the machine. The supporting arms for the troughs being hinged at their outer ends, the entrance edges of the scoops will always engage with the trough bottoms. It will also be noted 45 that the scoops are secured to the arms at their outer ends and extend toward the pivoted ends of the arms. This arrangement permits the scoops to ride more easily in the troughs and reduces strains.

My improved machine is of very large capacity in comparison with its size and weight. The material is fed into the inner trough where it is given a preliminary crushing and grinding treatment by the heavy rollers 39 and 40 and is then transferred successively 50 to the outer concentric crushing and grinding zones where it is acted upon by the rollers 57, 58, 59 and 57', 58' and 59', the finished product being delivered from the scoop 80. Owing to the long aggregate 60 length of grinding trough, raw material

can be continuously fed into the machine and finished material continually discharged therefrom, the machine operating therefore at maximum efficiency.

If the material treated is moist or sticky, 70 as for example where rock asphalt is being treated, scrapers or scarifiers in the form of rods 81 may be provided for engaging with the floors of the troughs to loosen up and scrape therefrom any material which may 75 stick thereto, upper and lower supporting frames 82 and 83 secured to the beam 50 being provided in which the rods may vertically reciprocate, weights 84 being preferably provided at the upper ends of the rods 80 for urging them downwardly against the material.

I do not of course desire to be limited to the exact construction and arrangement shown and described as modifications can 85 no doubt be made which would still come within the scope of the invention.

I claim as follows:

1. In a crushing machine of the class described, the combination of the supporting 90 frame work, a horizontal table having a plurality of concentric troughs, means for rotating said table on its axis, crushing rollers engaging said table in the respective troughs, means for feeding material to the 95 inner trough, an arm hinged at one end to said supporting frame work and extending over said table with the direction of travel thereof, a scoop secured near one of its ends to the free end of said arm and extending under said arm and toward the hinged end thereof in a direction opposite to that of rotation of said table, the inner end of said scoop resting against the bottom of the inner trough and the other end extending over the 100 trough rim to the next trough whereby material is scooped up from the inner trough and discharged into the adjacent trough, said arm being under tension during such 105 scooping operation and said arm being vertically free to permit the scoop edge to at all times rest against the bottom of said inner trough.

2. In a crushing machine of the class described, the combination of a horizontal 115 table having a plurality of concentric troughs, means for rotating said table on its vertical axis, crushing rollers engaging said table in the respective troughs, means for feeding material to the inner trough, a supporting frame stationarily secured above 120 said table, a plurality of arms pivoted at one end to said supporting frame and extending over said table one to each of said troughs in a direction corresponding to the direction 125 of rotation of said table, a scoop for each arm secured to the outer end thereof and extending toward the hinged end of said arm in a direction opposite to that of rotation of said table, the inner end of each 130

scoop resting against the bottom of respective trough and the other end extending over the trough rim to the next adjacent trough whereby material is scooped up from one 5 trough and discharged into the next trough, said arms being under tension during operation of the machine and being vertically

free to permit the scoop edges to at all times rest against the bottoms of said troughs.

In witness whereof, I hereunto subscribe 10 my name this 30th day of September, A. D., 1918.

WILLIAM G. STEVENSON.
